BENJAMIN BRODIO, OF NEW YORK, N. Y., ASSIGNOR TO THE SUPERHEATER COMPANY, OF NEW YORK, N. Y.

METHOD OF OPERATING OIL STILLS

Application filed May 31, 1923. Serial No. 642,554.

The present invention relates to stills and similar apparatus in which oil, particularly viscous oil, or other similar material, is heated while being forced through the apparatus. One of the objects of the invention is to provide a method for reducing the amount of work required to force the fluid through the apparatus or to reduce the pressure drop, if the same amount of power is used. Another object is to provide an improved method for permitting gases liberated in one portion of the apparatus, where its presence is objectionable to escape to another part where it will not interfere with the function of the apparatus. A further object is to reduce the amount of deposition of carbonaceous and other solid material within the still. Other objects will appear from the following description.

The invention is illustrated in the accompanying single sheet of drawings, in which Fig. 1 is a transverse sectional view of a still in which my invention is used; and Fig. 2 is an enlarged sectional view of a valve forming part of my invention.

The space within housing 1 is divided by partition 2 into the two portions 3 and 4, which communicate at the top through opening 5. In the lower part of space 3 there is placed the oil burner 6. 7 is a connection to the stack.

Within this housing is arranged the still proper. It is divided into two sections, one of which fills the major portion of the space 4, the other occupying the upper part of space 3. Each consists of a series of pipes 8 connected in such a manner by return bends or loops that the flow of the liquid to be heated occurs successively through them in a serpentine path. The liquid enters at pipe 9, flows through the serpentine coil in the space 3, and leaves at its upper end. It flows thence through pipe 10 to the lower end of the serpentine coil in space 4, leaving it at the upper end through pipe 11.

The oil, or other liquid to be heated, enters the heating coils in a cold, and therefore relatively very viscous state. Its frictional resistance is correspondingly high, and the quicker this can be reduced, the better.

While the advantages, from a thermo-dynamic standpoint, of having the heating medium flow in a direction opposite to that of the flow of the medium to be heated are appreciated by me, I purposely sacrifice them to a certain extent in my invention in order to secure other advantages, which, in the relations mentioned, outweigh them in my opinion. In the space 4 the flow of the gases is downward, and the flow of the oil is generally upward, and this arrangement is therefore in accordance with the principle spoken of. But if the cold oil were introduced directly at the lower end of the coils in space 4 with the idea of reducing the temperature of the gases to the lowest possible point, it would be found that, on account of the relatively cool gases encountered by the oil, a comparatively large number of coils would have to be traversed by it before its viscosity would be materially reduced. This involves a large amount of work and necessitates powerful pumps and excessive consumption of energy by them in the form of steam or electric current.

To illustrate the point by figures, we may take the case of a certain American heavy oil. The viscosity in Saybolt-seconds of this oil at a temperature of 50° F. is 1030; at 150° it is only 95. Forcing a certain amount of this oil at 50° through a pipe of a given size and length results in a pressure drop more than ten times as great as if the oil were at 150. It is therefore highly desirable to raise the temperature of the oil through say the first 100 degrees as quickly as possible.

My invention contemplates sending the oil first through a small number of coils exposed to the most intense heat of the furnace, the oil preferably entering at the point nearest the furnace, as in the illustrative form. At this high temperature the viscosity is rapidly reduced to a point where the oil flows freely, so that relatively little force is required to move it through the still. Were the oil introduced into the coil at the point where the gases are coolest, it would have to flow through several times as many coils before attaining the same temperature. As by far the most effort of the pump is ex-

pended in forcing the oil in its cool state, and the effort after the first viscosity has been reduced is almost negligible, the value of the arrangement will be obvious.

One advantage is also incidentally obtained, and may here be mentioned, and that is that the coils nearest the furnace, which are exposed to the severest conditions, and which, with pure counterflow, would have the hottest liquid on the inside, by the present arrangement have the coolest liquid on the inside and are thereby more effectually protected from overheating.

More important is the advantage of reduction of amount of deposit of solids in the pipes. The combustion gases at the point where oil is hottest, are somewhat reduced in temperature, and the final heating occurs with a smaller temperature difference between oil and combustion gases and with the walls therefore not so hot than would be the case if the gases struck the coils, in which the hottest oil is found, directly after leaving the furnace. The effect of this is a lessening of the deposition of carbon and other solid matters in the coils where the oil is in its final heating stages.

At the outlet end of the coils in space 3 there will at times be some gaseous constituents which have been liberated by the heating of the oil and are now mixed with it in a free state. Their presence may result in disturbances in the circulation of the oil beyond this point, particularly the downward course in pipe 10. A further feature of my invention has for its purpose the disposal of such gases.

For this purpose I connect the highest point of the coil in space 3 to pipe 11 by means of a pipe 12 and a special valve 13.

The valve 13 comprises a body A and a ball B. The inlet C of the valve communicates with pipe 12 and the outlet D of the valve with pipe 11. The outlet D has formed on its inner end the seat E of such shape that ball B will, when engaging the seat, close the outlet, as shown in the dotted outline of the ball. F is an opening in the body A, closed by a plug G; the purpose of the plugged opening being to make possible the insertion or removal of the ball B. The portion of the valve body in which the outlet D is formed, is somewhat higher than the rest of the body, and the inside cavity of the valve body is so shaped that the ball B may freely roll away from the seat E under the influence of gravity, and occupy a position, as shown in full lines, in which it will not obstruct communication from pipe 12 to pipe 11.

The material and structure of the ball B are such that the ball will float on the liquid flowing through the still, but is heavier than the gas that may form in the first coil.

As long as pipe 12 and valve body A are filled with the liquid the ball B will float in

the liquid, and will be at the upper cavity, and there it will be held against its seat by the pressure of the liquid. This pressure will be greater than the pressure in pipe 11 by an amount equal to the pressure drop experienced by the liquid in flowing from the outlet of the coil in space 3 to the outlet of the coil in space 4. The valve therefore effectually shuts off any flow of liquid.

If now any gases collect in the outlet from the first coil and in pipe 12, the ball B will leave its seat and fall into the position shown in full lines, thus opening passage D and permitting the escape of the gases to pipe 11. It should be noted that opening D is comparatively small and the slight unbalanced pressure on ball B is overcome by the weight of the ball, so that the valve opens promptly when gases accumulate. After the discharge of the gases the valve will again be seated and kept closed by the unbalanced pressure difference.

While I show and describe only one form of valve to accomplish my purpose, I can obviously substitute some other form for it, if it performs the same function.

What I claim is:

The method of heating a viscous liquid by means of a gaseous heating medium comprising the steps of reducing the viscosity rapidly by initially imparting heat to the liquid while the heating medium is at a high temperature, thereafter completing the transfer of heat from the medium to the liquid under counterflow conditions without permitting any vapors to separate out from the liquid during such second heating, removing any gaseous portions from the liquid at the end of said initial heating, and adding said gaseous portions to the liquid at the end of said second heating.

BENJAMIN BRODIO.
